REFRIGERATOR

William T. Hedlund, New Rochelle, N. Y., assignor
to Servel, Inc., New York, N. Y., a corporation
of Delaware

Application July 23, 1937, Serial No. 155,329

12 Claims. (Cl. 62—108.5)

My invention relates to refrigerators, and more particularly to freezing trays for producing ice and other frozen matter in household refrigerators.

It is an object of my invention to provide an improvement whereby freezing trays having a front closure member are effectively sealed in a compartment of a cooling element or evaporator of a refrigerator. I accomplish this by providing mechanism to automatically urge a tray rearward in a freezing compartment when the tray is inserted in the compartment.

The tray front or closure member is preferably provided with a sealing strip or gasket to prevent the escape of cold air from the freezing compartment when the tray is positioned therein. The mechanism to urge the tray rearwardly may be associated with a lever operative to break the ice bond between the tray bottom and its supporting surface.

The invention, together with the above and other objects and advantages thereof, will be better understood from the following description and accompanying drawing forming a part of this specification, and of which:

Fig. 1 is a front view of the upper part of a household refrigerator having a cooling element provided with freezing compartments adapted to receive trays embodying the invention;

Fig. 2 is a fragmentary side sectional view of the cooling element shown in Fig. 1 to illustrate more clearly a tray positioned therein;

Fig. 3 is a fragmentary sectional view similar to Fig. 2 with the tray partly withdrawn from the cooling element; and,

Figs. 4 and 5 are fragmentary sectional views similar to Fig. 3 illustrating modifications of the invention.

Referring to Fig. 1, a refrigerator 10 is provided with a thermally insulated storage compartment which is cooled and maintained at a desired low temperature by a cooling element or evaporator 11. The cooling element 11 is provided with a plurality of freezing compartments adapted to receive trays 12 for freezing water and the like.

As shown in Fig. 2, the forward end of each tray is provided with side plates or reinforcement members 20 to which are secured a tray front or closure member 13. The tray front 13 is preferably provided with a flange 16 about the periphery thereof to receive a gasket or sealing strip 15. When the tray 12 is positioned in the freezing compartment 11a, the gasket 15 bears against a front baffle plate 28 of the cooling element 11 to provide an air-tight seal and prevent

the escape of cold air from the freezing compartment. The tray front 13 may be formed with a rounded portion 14 which is open at the bottom to provide a finger grip for the tray.

In order to break the ice bond which is formed between the bottom of the tray and the shelf 30 of the cooling element 11, a lever 17 is pivoted at 21 to the side plate 20. The lever 17 extends through an opening in the tray front 13 and is provided with a handle portion at the outer end thereof. The lever 17 is provided with a curved or rounded portion 18 which is adapted to contact and bear against a lug or projection 19 which extends inward from a side wall of the cooling element 11. When the outer end of lever 17 is raised the portion 18 is lowered and bears against the lug 19, whereby a separating force is produced between the tray 12 and shelf 30 to break the ice bond formed at the bottom of the tray.

In accordance with my invention, in order to automatically urge the tray 12 rearwardly when it is positioned in the freezing compartment, I provide mechanism which is operatively associated with the tray and lug 19. I accomplish this by employing a snap-acting mechanism including a lever 22 having downward extending bifurcated arms 23 and 24. The upper end of lever 22 is pivoted at 28 to lever 17 and movement thereof is limited by spaced pins 26 and 27 which are fixed to lever 17. A coil spring 25 having one end secured to lever 17 and the other end secured to lever 22 is provided to impart a snap-acting movement to lever 22 so that the latter will assume either one of the positions shown in Figs. 2 and 3.

The operation of the mechanism just described is substantially as follows: When the tray 12 is inserted in freezing compartment 11a the lever 22 is in the position shown in Fig. 3 with the right-hand arm 23 above the lug 19. This permits the arm 23 of lever 22 to pass the lug 19 and, when the tray is moved rearward a sufficient distance, the lug 19 contacts the left-hand arm 24. With continued rearward movement of tray 12 the lever 22 is rotated about the pivot 28 and, when the spring 25 has moved past its dead-center position, the lever 22 will move to the position shown in Fig. 2. In moving to this position the right-hand arm 23 of the lever contacts the lug 19. Due to the tension of coil spring 25 the tray 12 is automatically urged rearward whereby the tray front 13 effectively bears against the front baffle 28. By providing the gasket 15 the tray 12 is effectively sealed within freezing compartment 11a.

ment 11a and the escape of cold air is prevented.

With the tray positioned in freezing compartment 11a heat is removed from the tray bottom through the shelf 30 due to the production of cold by the cooling element. Any moisture between the tray bottom and shelf is frozen due to such removal of heat, thus firmly uniting the parts. To break this bond the outer end of lever 17 is raised, as explained above, so that the rounded part 18 bears against the lug 19 to exert a separating force between the tray and shelf.

With the ice bond broken at the tray bottom, the tray 12 may be moved forward by the finger grip 14. With initial forward movement of the tray 12 the lever 22 is rotated about its pivot 28 and, when the spring 25 has moved past its dead-center position, the lever 22 will snap to the position shown in Fig. 3. In this position the right-hand arm 23 is above the lug 19, thereby permitting withdrawal of the tray from the freezing compartment 11a.

In Fig. 4 I have shown a modification in which the tray release lever 17 is omitted. The lever 22a having arms 23a and 24a is pivoted at 28a directly to the side plate 20a. The pins 26a and 27a which limit the movement of lever 22a are fixed to side plate 20a. The coil spring 25a is secured to the lever 22a and to the side plate 20a. The operation of this modification is the same as that described above in connection with the embodiment shown in Figs. 2 and 3, with the exception that no mechanism is provided to break the ice bond between the tray bottom and shelf 30 of the cooling element.

In Fig. 5 I have shown a further modification in which the tray release lever 17b is arranged to impart an initial forward movement to tray 12 when the outer end thereof is raised upward. In this modification the lever 22b is pivotally connected to a side plate 20b instead of to the tray release lever, as shown in Figs. 2 and 3. The coil spring 25b is secured to the side plate 20b and to lever 22b. The pins 26b and 27b are fixed to lever 17b to limit the movement of lever 22b.

In this modification, when the tray is positioned in the freezing compartment, upward movement of the outer end of lever 17b lowers the pin 27b. The pin 27b bears against the lever 22b and immediately starts moving the latter when the outer end of lever 17b is raised to break the ice bond at the tray bottom. With sufficient downward movement of pin 27b the coil spring 25b is moved past its dead-center position whereby the right-hand arm 23b will move above the lug 19. At the same time the left-hand arm 24b bears against the lug 19 to cause forward movement of the tray when the ice bond is being broken.

Although particular embodiments of the invention have been shown and described, it will be apparent that various modifications and changes may be made without departing from the spirit and scope of the invention, as pointed out in the following claims.

What is claimed is:

1. The combination with a cooling member having a freezing compartment, of a tray member adapted to be inserted in and withdrawn from said compartment, and means carried by one of said members and adapted to co-operate with a part of said other member to urge said tray rearward when the latter is being inserted and moved in said compartment.

2. The combination with a cooling element having a freezing compartment, of a tray adapted

to be inserted in and withdrawn from said compartment and having a front closure member, and mechanism actuated when said tray is being inserted in said compartment to urge said tray rearward whereby said front closure member bears against a wall of said cooling element.

3. The combination defined in claim 2 and including a sealing strip fixed to said closure member to provide an air-tight seal when said tray is positioned in said compartment and urged rearwardly therein.

4. The combination with a cooling element having a freezing compartment, of a tray adapted to be inserted in and withdrawn from said compartment, a lever carried by said tray and operative to lift said tray when the latter is positioned in said compartment, and mechanism associated with said lever and operative to urge said tray rearward when the latter is inserted in said compartment.

5. The combination with a cooling element having a freezing compartment, of a tray adapted to be inserted in and withdrawn from said compartment, said tray having a front closure member provided with an opening, a lever carried by said tray and having a handle portion extending through said opening, said lever being operative to lift said tray when the latter is positioned in said compartment, and mechanism associated with said lever and operative to urge said tray rearward when the latter is inserted in said compartment.

6. The combination with a cooling element having a freezing compartment, of a tray adapted to be inserted in and withdrawn from said compartment, a member pivotally carried by said tray and adapted to cooperate with a part of said cooling element, and means including said member to urge said tray rearward when the latter is inserted in said compartment and said member contacts and is moved by said part.

7. In a cooling member having a freezing compartment and a tray member adapted to be inserted in and withdrawn from the compartment, the improvement which consists in providing an abutment on one of the members, and mechanism on the other of the members arranged to contact said abutment due to movement of the tray member as it is inserted into position in the compartment, said mechanism being operative to urge the tray member rearward when it is actuated by contacting said abutment.

8. The improvement defined in claim 7 wherein said mechanism is moved from a first to a second position to urge the tray member rearward when it is actuated by contacting said abutment, and said mechanism contacts said abutment to move it from the second to the first position when the tray member is withdrawn from the compartment.

9. The improvement defined in claim 7 which further includes providing a lever on one of the members which is capable of co-operating with the other of the members to raise the tray member when the latter is in position in the compartment, and a connection whereby said mechanism imparts forward movement to the tray member when said lever is actuated to raise the tray member.

10. In a cooling element having a freezing compartment and a tray adapted to be inserted in and withdrawn from the compartment, means responsive to movement of the tray when it is being inserted in the compartment to urge the tray rearward, and means to limit rearward

movement of the tray effected by said last-mentioned means.

11. The combination with a cooling element having a freezing compartment, of a tray adapted to be inserted in and withdrawn from said compartment, and mechanism actuated by movement of the tray as said tray is inserted in said compartment to urge said tray rearward.

12. The combination with a cooling element having a freezing compartment, of a tray adapted to be inserted in and withdrawn from said compartment, and snap-acting mechanism actuated by movement of the tray as said tray is inserted in said compartment to urge said tray rearward.
